Patented Aug. 11, 1925.

Des. 67,974

UNITED STATES PATENT OFFICE.

MARTIN T. ROBINSON, OF LONG BEACH, CALIFORNIA.

DESIGN FOR A LOUD SPEAKER.

Application filed July 1, 1925. Serial No. 13,967. Term of patent 8½ years.

To all whom it may concern:

Be it known that I, MARTIN T. ROBINSON, a citizen of the United States of America, and a resident of Long Beach, in the county of Los Angeles and State of California, have invented a certain new, original, and ornamental Design for Loud Speakers, of which the following is a specification, reference being had to the accompanying drawing, forming a part hereof, and in which

The figure is a perspective view of a loud speaker showing my new design.

I claim:

The ornamental design for a loud speaker as shown.

MARTIN T. ROBINSON.
